UNITED STATES PATENT OFFICE.

ALEXANDER MCLEAN NICOLSON, OF NEW YORK, N. Y., ASSIGNOR TO WIRED RADIO, INC., OF NEW YORK, N. Y., A CORPORATION OF DELAWARE.

DIRECT-ACTING SOUND-REPRODUCING DEVICE.

Application filed April 2, 1927. Serial No. 180,419.

This invention relates to sound reproducing apparatus and more particularly to apparatus arranged to be operated by electrical oscillations, corresponding to the sound to be reproduced, and operating to convert such oscillations into sounds corresponding thereto.

It is an object of this invention to provide improved apparatus utilizing the phenomena of resonance or partial resonance, to convert electrical oscillations into sound.

It is a further object of this invention, to provide improved apparatus of the class described, utilizing a multiplicity of direct acting sound radiating elements such as sounding boards, having different natural frequencies, for converting electrical oscillations into sound.

It is a further object of this invention to provide improved apparatus for converting electrical oscillations into sound corresponding as closely as possible to the original sound which it is desired to reproduce. Still other objects of my invention will be apparent from the specification.

The features of novelty which I believe to be characteristic of my invention are set forth with particularity in the appended claims. My invention itself, however, both as to its underlying principles and as to its practical application will best be understood by reference to the specification and accompanying drawing, in which the single figure is a front elevation partly in section of apparatus according to my invention.

In accordance with my invention, I provide a plurality of direct acting sound radiating surfaces such as sounding boards. The sounding boards are so constructed and arranged that each has a different natural frequency: to this end, they may be of different sizes, shapes, materials, or may differ in physical characteristics in any way desired to provide the desired operating characteristics.

The said sounding boards are chosen so that their natural frequencies are distributed over the range to be covered, are secured together in spaced relation by means of one or more mechanical connections which may act simultaneously as a medium for transferring the acoustic vibrations to each of the sounding boards.

A suitable driving means adapted to con-

vert electrical oscillations into corresponding acoustic vibrations is associated with the chain of sounding boards already described, in such manner as to drive the same. The driving means may be any desired arrangement operating to convert electrical oscillations into acoustic vibrations such for example as an electro-magnetic unit, but for certain purposes I prefer to use a piezo-electric crystal device such for example as a crystal of Rochelle salt exhibiting the well known "hour-glass" configuration. Said crystal device or other suitable driving means is associated mechanically with at least one of the sounding boards or with the vibration transmitting connection therebetween or with both, and is provided with a pair of electrodes between which may be impressed the electrical oscillations corresponding to the sounds which it is desired to reproduce.

My invention is shown in the accompanying drawing in side elevation, illustrating the multiplicity of sounding boards and the connection thereof with the source of sound vibrations.

Referring now more particularly to the drawing, 1, 2, 3 and 4 designate respectively a plurality of sounding boards of different size and shape, and if desired of different material such as different kinds of wood, or if desired material other than wood, such for example as hard rubber, bakelite, or even metal if desired. The driving plate 5 preferably of elastic metal such as steel or duralumin is provided adjacent the sounding board 4 and the assemblage is maintained in proper spaced relation by means of suitable bolts 6 and 7 passing through each of the sounding boards and through the plate 5.

Suitable spacing members 8 may be interposed upon the bolt 6, and similar spacing members 9 upon the bolt 7 for the purpose of maintaining the various sounding boards at the desired distance from each other. Suitable nuts 11 mounted upon the bolt 7 and similar nuts 12 mounted upon the bolt 6 are provided for maintaining the various elements in proper position and suitable washers 13 of leather, felt, or other absorbent material are interposed between the nuts and the plate 5 and any other metal to metal joints where necessary to prevent rattling.

A suitable piezo-electric crystal 10 such for

example as a crystal of Rochelle salt exhibiting the well known "hour-glass" configuration is mounted upon the plate 5 in any suitable manner as for example by cementing 5 thereto with Rochelle salt "melt" comprising Rochelle salt from which the desired amount of water has been removed by heating it at a temperature above its melting point. For the purpose of maintaining the crystal in position 10 and for applying a compressive stress to it, there may be provided a U shaped clamp 15 having ends 16 and 17 adapted to be mounted upon bolts 6 and 7 respectively and to be secured in position thereon by means of suitable nuts 18 and 19. The crystal 10 is protected by a suitable casing 22 having an opening therein to permit the cushion 23 to extend therethrough. The cushion 23 may be 15 of suitable material such as rubber, cork, leather or soft metal, or the like, and is in turn operated by a spacing element 24. The casing 22 is provided with an extension 25 of flexible material such as copper on the outside of which is adapted to operate the clamping screw 26 having a head formed to engage the casing 25 and through it the cushion 24. The screw 26 may be provided with a slot in the outer end by means of which the same 20 may be positioned as desired, and a suitable lock nut 28 is also provided for the purpose of securing the parts in the proper position. A pair of electrodes are provided for operating the crystal 10.

In the form shown, the plate 5 may 35 constitute one of these electrodes and the other may be constituted by an interior electrode 21 mounted within the crystal. The exact form of these electrodes is, however, no part of this invention per se and other arrangements may 40 be substituted for that shown.

The spacer members 8 and 9 may be metallic if desired or may be wood provided with a metallic lining, and a rubber or felt or leather sleeve may be provided to surround each of 45 the bolts 7 and 6 for the purpose of preventing rattling if necessary.

The different sounding boards, as will be understood, may have different mass, damping, elasticity, etc., and the number and arrangement of sounding boards is so chosen 50 as to give a substantially flat response characteristic over the range desired.

While I have shown and described certain preferred embodiments of my invention, it 55 will be apparent that modifications and changes may be made without departing from the spirit and scope of my invention, as will be understood by those skilled in the art.

I claim:

60 1. An acoustic device comprising a plurality of sounding boards having different natural frequencies, means for converting electrical oscillations into acoustic vibrations for driving said sounding boards, and a pair of independent connections extending be-

tween separated points along said sounding boards for transferring vibrations from said means to each of said sounding boards.

2. An acoustic device comprising a plurality of sounding boards having different natural frequencies, means for converting electrical oscillations into acoustic vibrations, a pair of vibration transmitting links extending normal to each of said sounding boards for transferring sound vibrations 75 from said means to each of said sounding boards.

3. An acoustic device comprising a plurality of sounding boards having different natural frequencies, means for converting electrical oscillations into acoustic vibrations for driving said sounding boards, a pair of rod members extending normal to the plane of said sounding boards and securing said sounding boards in parallel spaced relation, 85 while transferring sound vibrations from said means to said sounding boards.

4. An acoustic device comprising a plurality of sounding boards of different sizes and shapes having different natural frequencies, 90 means for converting electrical oscillations into acoustic vibrations for driving said sounding boards, a pair of rod members extending normal to the plane of said sounding boards and securing said sounding 95 boards in parallel spaced relation, while transferring sound vibrations from said means to said sounding boards.

5. An acoustic device comprising a plurality of sounding boards having different natural frequencies, a pair of vibration-transmitting connections between said sounding boards, and means for converting electrical oscillations into acoustic vibrations and for applying 100 said vibrations to said connections. 105

6. An acoustic device comprising a plurality of sounding boards having different natural frequencies disposed in spaced relation, a plurality of vibration-transmitting connections between said sounding boards, and means for converting electrical oscillations into acoustic vibrations and for applying 110 said vibrations to said connections. 115

7. An acoustic device comprising a plurality of sounding boards of different sizes and shapes having different natural frequencies disposed in parallel spaced relation, a pair of vibration-transmitting connections between said sounding boards for maintaining said sounding boards in selected space relation, and means for converting electrical oscillations into acoustic vibrations and for applying 120 said vibrations to said connections. 125

8. An acoustic device comprising a plurality of sounding boards of fibrous material 125 of different sizes and shapes having different natural frequencies disposed in spaced relation, and a pair of vibration-transmitting connections between said sounding boards for maintaining said sounding boards in selected 130

space relation, an elastic metallic mounting plate secured to said vibration-transmitting connections, and means for converting electrical oscillations into acoustic vibrations 5 mounted on said plate.

9. An acoustic device comprising a plurality of sounding boards of fibrous material of different sizes and shapes having different natural frequencies disposed in spaced relation, and a pair of vibration-transmitting connections between said sounding boards 10

for maintaining said sounding boards in proper space relation, an elastic metallic mounting plate secured to said vibration-transmitting connections, and means for converting electrical oscillations into acoustic vibrations mounted on said plate. 15

Signed at New York, in the county of New York and State of New York, this 31st day of March A. D. 1927.

ALEXANDER MCLEAN NICOLSON.
